(57) **CLAIM**

The ornamental design for a breast pump collector bottle, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a perspective view of the breast pump collector bottle;

FIG. 2 is a front elevation of the breast pump collector bottle of FIG. 1;

FIG. 3 a rear elevation of the breast pump collector bottle of FIG. 1;

FIG. 4 is a side elevation of the breast pump collector bottle of FIG. 1;

FIG. 5 is a top plan view of the breast pump collector bottle of FIG. 1; and,

FIG. 6 is a bottom plan view of the breast pump collector bottle of FIG. 1.

In the drawings, colored areas are shown as stippled and transparent areas are shown with oblique lines.

Preferably, the colored portions appear in Pantone 2705 or equivalent.
